CLAIM

The ornamental design for a head for golf club, as shown and described.

DESCRIPTION

FIG. 1 is a perspective view of a head for golf club;

FIG. 2 is an elevational view thereof;

FIG. 3 is a left side view thereof; and,

FIG. 4 is a top view thereof.

The portion shown by broken lines is for illustrative purposes only and forms no part of the claimed design. The dashed lines show a borderline between the claimed design and other portion.
